UNITED STATES PATENT OFFICE.

CLARENCE E. PATTERSON, OF BROOKLYN, NEW YORK.

APPARATUS FOR CUTTING BOGS.

SPECIFICATION forming part of Letters Patent No. 359,541, dated March 15, 1887.

Application filed January 31, 1887. Serial No. 225,977. (No model.)

To all whom it may concern:

Be it known that I, CLARENCE E. PATTERSON, of the city of Brooklyn, county of Kings, and State of New York, have invented new and useful Improvements in Apparatus for Cutting Bogs, of which the following is a specification, reference being made to the accompanying drawings, forming part thereof.

My invention relates to apparatus for cutting bogs, which frequently grow in fields that lie in low lands; and it consists in a new and improved construction of such apparatus, whereby its cost is considerably reduced and its operation rendered very effective.

15 I will describe an apparatus embodying my invention, and afterward point out the novel features in the claim.

In the drawings, Figure 1 is a perspective view of an apparatus constructed according to 20 my invention. Fig. 2 is a longitudinal section of a portion of the same. Fig. 3 is a transverse section through the line *x x* of the portion shown in Fig. 2; and Fig. 4 is a transverse section taken on the line *y y*, Fig. 2, of one of 25 the cutters.

Similar letters of reference indicate corresponding parts in all the figures.

A A' designate knives or cutters, made of long thin strips of sheet-steel arranged in V- 30 shape form and having their inner edges beveled for cutting, and having their outer edges provided with stiffening-bars B B', extending along the entire length of said cutters. These bars B B' are rigidly secured to the cutters by 35 means of rivets or other suitable means. The front ends of the cutters are bent upwardly, and their outer edges are curved inwardly to form approximately a point. The rear ends of the cutters are united by a plate, C, resting 40 on and secured to the bars B B' and cutters A A' by screws D D', each of which passes through and secures the lapped ends of both cutters. An extension, C', of the plate C fills the angular space between the bars B B', and 45 thus serves to lock the cutters firmly in position.

E is a screw placed as near as practicable to the point of intersection of the cutting-edges of the cutters A A', and serves to hold that 50 portion closely together.

It will be seen by the foregoing construction that the cutters can be readily detached to facilitate their sharpening, when required.

The sides of the front portion of the plate C curve inwardly, and are beveled to form a narrow edge to allow the bogs to pass freely from the cutters after having been cut. Rearward of the plate C is an upward extension, C², to which the handles F F are secured by bolts or other suitable means. This extension C² is 55 provided with flanges C³ C⁴, to embrace the sides of the central piece of the handles and hold the latter firmly in position.

The handles F F may be of wood and of any suitable construction. As here shown they 60 consist of two handle-pieces with a central piece, F', the whole being secured together by a bolt, F², and a brace, F³.

G is a bail or yoke of semicircular form, and sufficiently high to pass over bogs, and is secured to the bars B B' by screws. 70

H is a draw-bar clipped firmly to the bail G, and it extends rearward, where it is secured to the central piece, F', of the handles F F, and the extension C² by screw-nuts. The front 75 end of this draw-bar is provided with a clevis, H', or other suitable device, whereby the apparatus may be drawn by horse-power.

By my improvements I make an apparatus for cutting bogs, which is very light and easily operated. The turned-up points of the cutters act as shoes and prevent digging into the ground, and where bogs occur in large numbers and in close proximity to one another the attendant is enabled by means of the handles to turn the said points of the cutters either to the right or left and avoid bogs that may be in their path, and so guide through or between them without difficulty. 85

Having now described my invention, what 90 I claim as new, and desire to secure by Letters Patent, is—

The combination of the cutters A A', bars B B', rigidly secured thereto, screw E, handles F F, plate C, bail G, draw-bar H, and clevis 95 H', substantially as described.

In witness whereof I have hereunto subscribed my name in the presence of two subscribing witnesses.

CLARENCE E. PATTERSON.
